UNITED STATES PATENT OFFICE.

GEORGE C. CLARK, OF EVERETT, WASHINGTON.

SURFACE-DRESSING MACHINE.

1,285,041.

Specification of Letters Patent. Patented Nov. 19, 1918.

Application filed December 3, 1917. Serial No. 205,253.

To all whom it may concern:

Be it known that I, GEORGE C. CLARK, a citizen of the United States, residing at Everett, in the county of Snohomish and State of Washington, have invented a new and useful Improvement in Surface-Dressing Machines, of which the following is a specification.

My invention relates to machines for use in dressing off surfaces which are irregular and uneven to produce surfaces of smooth contour and more particularly for dressing off surfaces composed of wood. It employs a cutting member, which is preferably in the form of a rotating cutter head, which is mounted upon a combination of carriages which are capable of traveling upon rails secured upon the surfaces which are to be dressed, suitable means being provided for adjusting the cutter head so that it may successively dress different sections of the surfaces by moving the device along the rails.

One of the principal uses of my invention is the dressing of the plank receiving surfaces of the ribs of wooden vessels, so as to secure a true and smooth outline for the reception of the planks. It is, however, evident that my device may be employed for dressing other surfaces than these.

My invention is capable of dressing surfaces which are plane or curved, and which occupy any angular position, whether horizontal, vertical, or any angle between.

The particular features of my invention which are novel and upon which I ask for patent, will be hereinafter set forth and then particularly pointed out in the claims.

In the accompanying drawings I have shown my invention embodied in a form of construction which I now prefer to use. This construction is, however, given only as illustrative of the principles embodied in my invention and not with any intention of suggesting that the same is the only construction which may be employed.

Figure 1 is a side elevation of my device shown in the position which it would occupy in dressing the under sides of beams.

Fig. 2 is an end view of the device shown in similar position.

Fig. 3 is a detail showing in end view and cross section on the line A—A of Fig. 1, mechanism employed for raising and lowering the transverse bars.

Fig. 4 is a section showing the manner of adjusting and locking the eccentrics used in adjusting the angular position or level of the cutter head mechanism.

Fig. 5 is a face view of a cutter head showing a form of construction which I have found excellently adapted for use in dressing off edges of wooden beams.

My invention has been particularly designed for the dressing off of the surfaces of ribs or frames of wooden ships preparatory to putting the planks thereon and I will so describe it, although it will be understood that it may be similarly used for dressing any other kind of surfaces wherein the conditions are at all analogous.

In the construction of wood vessels the timbers for forming the ribs and frames are cut as near as may be to the proper shape and thereafter being joined together, are put in place on the ways. In doing this it is impossible to get an absolutely true surface of the outer and inner edges of these frames so that when the planks are placed thereon they will have true bearing upon all of these frames.

It has heretofore been customary to dress these frames by hand so as to get a true contour of the plank receiving surfaces thereon. This has proven a slow and expensive operation and my machine is designed for use for doing this dressing off of the frames, which process is usually referred to as "dubbing" and this dubbing operation requires men who are expert in the use of an adz, and it is difficult to find men who can do this work satisfactorily.

The foundation for the operation of my machine consists of a trackway formed by two sets of rails 1 which are secured to the surface to be dubbed off or dressed. These rails may be, and I prefer to have them, ordinary T-head rails, such for instance, as

are used for making tracks upon which to run cars. The essential features of these rails is that they may be capable of being quickly and easily secured to the surfaces 5 to be dressed and that they have a head suitable for the reception and retention of the carriage wheels of my device. They should preferably, be of a size as will permit their bending enough to fit the curved 10 contour of the ship's surface.

These rails may be conveniently secured to the wood frames of a vessel by means of lag screws 10 which enter the body of the frames and which employ a bar or washer 15 11 which overlaps the base flange of the rail. Any suitable means for securing these in place may, however, be employed.

I prefer a carriage for each of these rails. Each carriage has two pairs of wheels 2, 20 which are provided with a flange at each side so spaced as to snugly fit over the side face of the head of the rail. The axis of these wheels is thus perpendicular to the surface being operated upon. As shown in 25 Figs. 1 and 2, each of these wheels is mounted upon a pivot 20 which is secured in a member 21 which latter is of a general L-shape, the pin 20 being fixed in one arm of the L and the other arm of the L having 30 ears formed therein to form part of a pivot or hinge joint. These ears 22 are made to intermesh, as is clearly shown in Fig. 2, and a bolt 23, extending through the same, clamps these together and with them the 35 upper end of a link or bar 3 which projects away from the surface being dressed.

These wheel-supporting members are held 40 toward each other by a bolt 24 so as to cause the wheels to closely engage the head of the rail. By slackening off on this bolt the two members 21 may be separated in such manner as to separate the wheels 2 and thus permit the carriage to be either placed upon or 45 removed from the rail.

Each carriage duplicates this device and the carriage parts represented in each case by a pair of wheels and their connected 50 parts, are connected to form the complete carriage, by means of a spacer rod 25, which rod is herein shown as passing through the inner end of the slot 30 which is formed in the link 3 and has clamping nuts 26 whereby the two links and their attached carriage 55 parts, may be rigidly secured by the rod 25.

The cutting member is represented as a head 4, which head, for the purpose herein illustrated, namely, the dubbing off of the ribs of a ship, is made as a face cutter. It consists of a disk 40 which is mounted upon a 60 shaft 41, the axis of said shaft being placed perpendicular to the surfaces being dressed, and is provided with cutting bits 42 and 43, the two kinds of bits being made with slightly different cutting edges so as to secure better

cutting action. The particular construction 65 of the cutter head is, however, not a part of my present invention and any other type which is found to work satisfactorily may be employed.

The shaft of the cutter head is herein 70 shown as a continuation of the shaft of an electric motor which is contained within the case 44. The motor is supplied with current through a wire cable which extends to any suitable point from which current may be 75 obtained.

The motor and the cutter head mechanism operated thereby are provided with means for supporting, adjusting and moving them upon the two transversely extending bars 5, 80 which bars are in turn supported by the arms 3 which extend outwardly from the carriages. These bars 5 are herein shown as being of rectangular cross section. They slide within blocks 50 which in turn are mounted 85 upon the arms 3 in such manner that they may be adjusted lengthwise of the latter. As herein shown, the blocks 50 are each provided with a flange or rib 51 which fits into the slot 30 in the arm 3. This prevents turning relative to the arm 3. The block is secured in adjusted position on said arm by means of a bolt 52 which screws into the flange 51 and beneath which is placed a plate 53 which acts as a washer, both for 90 this bolt and for the rod 6 by which an adjustment in elevation of the blocks 50 may be secured.

One side bar of the arms 3 is herein shown 100 as provided with teeth 31 and the rod 6 which passes through said slots is provided at each end with a pinion 60 which meshes with the rack teeth 31. By turning the rod 6, which may be done by applying thereto a crank 61, the rod 6 will be raised or lowered 105 and will, carry with it the blocks 50, and therefore the transverse bars 5. The rod or shaft 6 is provided with bearings in the blocks 50.

By this means the same ends of both bars 110 5 are adjusted alike and yet the adjustment of the opposite ends of the bars 5 may be different.

The frame of the motor 44 should be of such construction that it provides means for 115 movement of the motor, with its attached cutter head mechanism, lengthwise of the bars 5 and also it should provide an adjustment which will enable changing the axis of the cutter head relative to the plane of the 120 surface being dressed and relative to the plane of the bars 5. The construction herein illustrated by which these results are secured is as follows:

Two plates or bars 7 and 70 are secured 125 together with the greater part thereof spaced apart sufficiently to place one at each side of the bar 5. They therefore act as retaining

and guide members for the bear 5. Between the upper ends of the separated portions of the bars 7 and 70, are placed eccentrics 71, which eccentrics have shafts extending 5 through the two bars 7 and 70, and the outer end thereof secured to members by which they may be adjusted and held in such positions as will enable them to be employed for raising and lowering the frame relative to 10 the bars 5. I prefer to employ with each motor three of these members, two being at one side of the motor and engaging the same bar 5 and the other being centrally placed at the opposite side. In this manner 15 a three-point support is secured and the motor and cutter head mechanism is adjustable universally, so far as the position of its axis goes, within a certain range of movement.

20 The two eccentrics which are at the same side of the device, have arms 72 secured to their shafts and these arms are connected together, as by a link 73, which link is provided with a slot 74 at one or both ends, and 25 this link is secured to the crank arm 72 by bolts 75. By means of the slot 74, the two arms 72 at the same side of the machine, may be adjusted independently of each other to thereby shift the axis of the motor in one 30 direction and thereafter the adjustment up and down would be alike for both.

The single device which is at the opposite side of the machine, and in fact, one of the devices upon the side where two are employed, are preferably provided with a locking device, such as is illustrated in Fig. 4. The eccentric 71 has secured thereto a stem 76 which is axially bored to receive a clamping bolt 8. The sleeve 76 has secured thereto 40 a hand wheel 77, by which it may be turned and thereby turn the eccentric 71. The bolt 8 at its outer end has a small hand wheel 80 by which it may be turned, or the wheel 80 may constitute a nut which turns upon 45 the bolt 8. By this means the eccentric may be readily adjusted and then, when this adjustment is secured, clamping down by means of the bolt 8 will hold the eccentric in adjusted position, thus making the adjustment permanent. One clamping device 50 of this sort, it is preferred, shall be provided for each side of the machine.

Secured upon the frame of the motor is a nut 9, through which passes a threaded rod 55 90, which rod is mounted to turn with reference to one of the arms 3 of one carriage but is held against longitudinal movement. At the other carriage it is provided with a journal bearing, but not a thrust bearing. The 60 nut 9 is mounted so as to be fixed in position relative to movements of the carriage in a direction parallel with the length of the bars 5, but so that it may have a limited amount of movement transversely of these

bars. This may be secured by giving the 65 nut a rib of a width to fit between the bars 7 and 70 and by providing a plate 91, which is secured to one of the bars, as 7, and is provided with a flange 92 which engages the outer face of the nut and thus prevents 70 movement lengthwise of the bar 5.

A crank arm, as 93, may be secured to the end of bar 9, and by rotation of the same, the motor and its carriage may be moved along the bars 5 as desired.

In preparing to use this machine the first step is the placing of the rails 1 upon which the apparatus is supported and operated. These rails are preferably of such weight 80 that they may be bent so as to conform to the outer contour of the hull of the vessel, or whatever surface is to be dressed. The finished contour of the surface is determined largely by the position of the rails 1. These rails are preferably maintained in parallel 85 relation, although this feature is not strictly necessary. The distance between these rails is approximately some multiple of the width of the surface dressed by the cutter head at one movement.

When the rails are properly placed, the carriages are placed thereon and the bars 5 with the motor and cutter head, also put in place. The whole device may be conveniently maintained in connected form and 90 both carriages be put in place at once. The position of the bars 5 relative to the supporting arms 3 is adjusted so as to bring the cutter head 4 into position so as to engage, and remove as much as may be desired of the ribs, or whatever other surface 95 is to be dressed.

The fine adjustment of the cutter head both as to elevation and as to angular position, may be secured through the use of 100 the eccentrics 71. The connection between the transverse bars 5 and the arms 3 is secured by turning the shaft 6, until the proper position is obtained and then clamping the same in place by tightening the clamping 105 nut 62. When the parts of all have been properly adjusted with the cutter close up to one of the rails 1, the cutter is started and the entire machine is caused to travel along the rails 1, the cutter meanwhile dressing off 110 the surface of the ribs as may be necessary.

As the contour of this surface is determined by the contour given the rails, and as the rails will have a smooth and regular contour irrespective of the surfaces of the ribs, 115 120 these surfaces of the ribs will be dressed to a smooth and regular contour. After the machine has reached one end of the rails the shaft 90 is turned enough to shift the motor and the cutter head adapted thereto so 125 as to dress a strip which just meets or overlaps the one just dressed, and the device is run in the return direction along the rails.

In this way the device dresses a series of narrow strips until the space between the rails has been covered. The machine is then taken off the rails and the rails shifted to 5 operate upon a new belt.

The diameter of the cutter head 4 is preferably made that of the width of the narrower boards used for the planking. Where the contour of the ribs is rounded, the angular position of the cutting mechanism may 10 be adjusted to correspond, and the cutter head will cut a series of plane surfaces, each at an angle with the others and of a width to each receive a single plank. In consequence, the planks are given a true flat seating upon the ribs.

My device may be applied to dressing horizontal surfaces, whether from below or from above and also vertical surfaces, or 20 surfaces placed at any angle between. It may, therefore, be employed for rapidly dressing or dubbing off outer and inner surfaces of the ribs of vessels to receive the planking. At this work the result secured 25 is more even and true than can be obtained by hand methods, and also is much more rapid.

I have described this machine as used for dubbing off the ribs of wooden ships. It is 30 evident that it may be applied for dressing floors or any other kind of a surface to which it is possible to secure rails for guide purposes. The trueness of the finished surface is not dependent upon the original 35 surface which is being treated, but upon the trueness in direction of the rails which are secured thereon and which may be blocked out, or held away from the surface at any point, as may be necessary.

40. What I claim as my invention is:

1. In a surface dressing machine, in combination, trackway rails having laterally enlarged heads and adapted to be secured to the surfaces to be dressed, carriages adapted 45 to be secured upon said rails and having opposed double flanged wheels embracing the rail heads from opposite sides and means for adjusting the opposed wheels toward and from each other to thereby engage and 50 disengage the wheels with the rails.

2. In a surface dressing machine, in combination, two lines of rails adapted to be secured in parallel relation upon the surface to be dressed, two carriages adapted 55 each to run upon its line of rails and each having a pair of arms projecting away from the surface to be dressed, a pair of transverse bars extending between like arms of opposite carriages, means for securing said 60 bars to said arms for adjustment lengthwise of the supporting arms, and a motor driven cutter-head carried by said bars.

3. In a surface dressing machine, in combination, two lines of rails adapted to be se-

cured in parallel relation upon the surface 65 to be dressed, two carriages adapted each to run upon its line of rails and each having a pair of supporting arms separated lengthwise of the rails and projecting away from the surface to be dressed, a pair of transverse bars extending between like arms of opposite carriages, a rack and pinion adjusting connection between said transverse bars and the supporting arms, and a motor driven cutter-head carried by said bars. 70

4. In a device for dubbing off surfaces, in combination, track rails, carriages secured to travel on said rails, transverse connecting bars, supporting connection from said bars to the carriages containing means for adjustment of the connecting bars toward and from the surface being dressed, a motor driven cutter-head mechanism mounted to move along said transverse bars and a threaded shaft secured to turn in said supporting connection and in parallel relation with said transverse bars, and a nut engaging said shaft and secured upon the cutter-head mechanism. 80

5. In a surface dressing machine, in combination, two lines of rails adapted to be secured in parallel relation upon the face of the surface to be dressed, said rails having an enlarged or flanged head, a carriage for each rail having two pairs of double 95 flanged wheels spanning the heads of the rails from opposite sides thereof, said wheels mounted so as to be capable of being spread apart to permit removal of the carriage from the rails, a cutter head and actuating means 100 therefor and means for supporting said cutter head from the carriages to dress the surface between the rails.

6. In a surface dressing machine, in combination, two lines of rails adapted to be 105 secured in parallel relation to the face of the surface to be dressed, said rails having an enlarged or flanged head, a carriage for each line of rails having two pairs of double 110 flanged wheels spanning the heads of the rails from opposite sides thereof, said wheels at one side of the rail head being mounted on arms having a pivotal connection with the carriage, clamping means for holding said wheel-carrying parts together, a cutter- 115 head and its actuating means, and means for supporting said head from said carriages to dress the surface between the rails.

7. In a surface dressing machine in combination, two carriages adapted to run upon 120 separated guide rails, two guide bars connecting said carriages and maintained in separated and parallel relationship, a cutter-head and its actuating means having supporting and guiding engagement with said 125 guide bars, the supporting and guiding means containing two members engaging one guide bar and one engaging the other

and means for adjusting said supporting means independently of each other.

8. In a surface dressing machine, in combination, two lines of rails adapted to be secured to the surface to be dressed and in parallel relation, a carriage mounted to travel along each line of rails, two guide bars, means for supporting said guide bars from said carriages in separated and parallel relation with each other and with the surface to be dressed, means for independent

adjustment of opposite ends of said guide bars toward and from the rails, a cutter-head carriage mounted to move along said guide bars, a cutter-head and actuating means therefor carried by said carriage, and means for adjusting the axial position of said cutter head.

Signed at Seattle, Washington, this 26th day of November, 1917.

GEO. C. CLARK.
